TUBEFLO SECTION

William Bisch, Holmdel, N. J., assignor to The Griscom-Russell Company, New York, N. Y., a corporation of Delaware

Application November 16, 1945, Serial No. 629,050

3 Claims. (Cl. 257—241)

1

This invention relates to heat exchange apparatus and, more particularly, to an improved construction of heat exchanger.

In numerous industrial operations it is desirable or essential that heat be economically transferred from a comparatively hot fluid to a fluid of lower temperature. Thus, for example, in oil refinery work the efficient operation of the plant often depends upon the completeness with which the heat content of different fluids is interchanged at different stages of their flow. Not infrequently the temperatures of both the hot fluid and the cooler fluid are not only comparatively high but also a comparatively large temperature difference exists between them. The mechanical construction of the heat exchanging device employed under such conditions and for such purpose is an important item, since this construction determines the thermal efficiency and economy of operation as well as the adaptability of the device to various installations.

In general, an economical heat exchanging device should provide the maximum thermal efficiency consistent with reasonable initial and maintenance costs and should be constructed to provide for easy cleaning of the fluid passages and fluid-tight joints between its component parts. In certain processes it is desirable or essential that one or both of the fluids between which an exchange of heat is desired be delivered not only at comparatively high temperature but also at comparatively high pressure, and accordingly the heat exchanging device should be capable of withstanding high pressures at high temperatures without danger of leakage or rupture.

The primary object of the present invention is to provide an improved heat exchanger for effecting the transfer of heat between various kinds of fluids at extremely high pressures and temperatures without danger of leakage or rupture.

In United States Patent 2,013,187, issued September 3, 1935, to Joseph Price and assigned to the same assignee as the present application, there is described and claimed a heat exchanger device of the type in question which is constructed with comparatively thin metal tubes of steel or other suitable material, such tubes passing through openings in a plurality of metal plates, the plates being spaced closely and uniformly along the tubes. The tubes are expanded into intimate heat exchanging contact with the plates by drawing an expanding device through the tubes.

While heat exchangers of such construction

2

have reached a high degree of commercial success, large quantities of them having been manufactured and being now in use, nevertheless the construction possesses limitations. For example, the tubes cannot nest against one another but must be spaced apart, and, in order for the fins to have sufficient strength it is necessary for the tubes to be spaced apart not less than about $\frac{1}{4}$ inch and excess metal is required at the ends and sides of the fins. The weight of the fins consequently is a considerable factor and tends to make the heat exchanger heavy. Furthermore, the center-to-center distance between the tubes is fixed by the expanding machine and prohibits the use of tubes of different size in the same unit without increasing the resistance to heat flow between the tubes.

The present invention aims, more specifically, to overcome these difficulties and to provide a tube-to-tube heat exchanger adapted for use at high pressures and temperatures having a greatly reduced resistance to heat transfer and which is lighter in weight, more compact, easy to clean and tends to keep itself clean.

Another object of the invention is to provide a heat exchanger of the type described in which tubes of different size may be employed without reducing the efficiency of heat transfer, and thereby enabling the proper velocity ratio between the two fluids to be maintained.

30. A further object of the invention is the provision of an improved method of constructing heat exchanging devices of the type described.

The invention will be understood from a consideration of the accompanying drawings and of 35 the appended claims, certain modifications being illustrated for the purpose of exemplifying the invention. In these drawings:

Fig. 1 is a side view of a heat exchanger unit constructed according to the preferred embodiment 40 of the invention;

Fig. 2 is an enlarged view, partly in elevation and partly in section, of the right hand end portion of the device shown in Fig. 1;

Fig. 3 is a cross-sectional view taken on line 45 3—3 of Fig. 1;

Fig. 4 is a view similar to Fig. 1 of a modified form of heat exchanger unit;

Figs. 5 and 6 are views showing steps in the manufacture of the preferred embodiment of the invention;

Fig. 7 is a cross-sectional view of a modification;

Fig. 8 is a cross-sectional view of another modification; and

Fig. 9 is a side view of one of the tubes used in the modification shown in Fig. 8.

Referring to the drawings, particularly Figs. 1 and 2, the heat exchanger unit of the invention comprises generally a plurality of tubes or pipes T₁, T₂, T₃ and T₄ arranged side by side and nested against one another in parallel relation leaving spaces or pockets between them extending lengthwise substantially from end to end of the unit. In these pockets are elongated strips or bars forming cores C₁ and C₂ of good heat conducting material such as copper, aluminum or a suitable alloy. The cores may also be made of steel. The tubes and cores are secured together throughout their length by brazing or welding, thereby uniting their contacting surfaces to provide paths having low resistance to the conduction of heat between the tubes.

Tubes T₁, T₂, T₃ and T₄ are preferably comparatively thin walled and may conveniently comprise seamless drawn tubes of steel or other suitable metal. The elongated strips or bars which form the cores may take various shapes, and as shown in Figs. 2 and 5 may comprise four outer core strips C₁ within the lengthwise pockets between the tubes, and two inner core strips C₂ of smaller cross-sectional area within the internal spaces or pockets. This results in two of the tubes—for example tubes T₂ and T₄, being in contact with one another, and the other two tubes T₁ and T₃ being spaced apart from each other but in contact with each of the tubes T₂ and T₄. The cross-sectional shape of the device is approximately that of an ellipse.

The outer core strips C₁ are preformed with curved inner surfaces which conform to the curvature of the tube surfaces. The apex 1 at the intersection between these curved surfaces is preferably flattened as shown in Fig. 5 to facilitate manufacture of the core strips and their assembly with the tubes. The inner core strips C₂ are preformed with substantially equal sides of the same curvature as the tube surfaces. Their apexes 2 are blunted or flattened in a similar manner to the apexes 1 of core strips C₁. As shown in Fig. 5, small air spaces exist between the apexes 1 of the outer cores C₁ and the apexes 2 of the inner cores C₂. These are eliminated during the brazing or welding operations, as will be mentioned further below, so as to provide continuous metallic paths for the flow of heat between the tubes.

Arrangement is made for one or more of the tubes to carry a comparatively hot fluid, and for the remainder of the tubes to carry a comparatively cool fluid. It is generally preferred to employ each unit of the heat exchanger as a double pass heat exchange device, although this arrangement is not essential to the invention. Thus in the disclosed embodiment means are provided for passing a comparatively hot fluid through the tubes T₂ and T₄ in succession and for passing a comparatively cool fluid through the tubes T₁ and T₃ in succession. The comparatively hot and cool fluids may be conducted to the tubes by the use of a stationary head 3 (Figs. 1, 2 and 4) at one end of each unit, and by return connections 4 and 5 at the opposite end. In order to make the connections with head 3 the unit is provided with an end flange 6. The ends of the tubes may be secured to flange 6 in an appropriate manner to withstand the operating pressure. As indicated at 7 in Fig. 2 the flange and tubes are welded together. The flange is secured to head 3 by means of a series of bolts 8.

At the opposite end of the heat exchanging device the return connections 5 and 6 may conveniently comprise return bends formed of the same material as the tubes and welded to these tubes as indicated at 9 and 10, respectively. To accommodate these connections the outer ends 11 of tubes T₂ and T₄, respectively, are offset so that the outer return bend 4 encompasses the inner return bend 5. To facilitate the offsetting of tubes T₂ and T₄ a strengthening fin or flange 12 is provided to surround the heat exchanger tubes as shown in Figs. 1 and 3. Fin 12 is of sufficient strength to withstand the bending stresses accompanying the formation of the offset portions in the ends 11.

In the heat exchanger unit as thus constructed, the flow path for each of the fluids has substantially uniform area from ingress to egress, tending to keep the unit clean, that is, free of scale or deposit from the fluid passing through it. Also in case such deposit does accumulate through extended use the flow passages are not difficult to clean.

It will be understood that head 3 contains ingress and egress channels (not shown) for conveying the respective fluids to and from the two pairs of tubes. Thus the comparatively hot fluid may flow into the end of tube T₂ from head 3, then through the tube to the return bend 4 and thence through tube T₄ back to head 3 where it enters an egress channel therein. Also the comparatively cool fluid may enter tube T₁ from a separate inflow channel in head 3 and flow through tube T₁, return bend 5 and tube T₃ where it enters a fourth channel in head 3. The heads 3 may be constructed, for example, as shown in the previously mentioned U. S. Patent, and any desired number of the heat exchanger units may be assembled to form a heat exchange apparatus of any desired capacity as disclosed in that patent. Thus a plurality of such units may be assembled in series relation by employing heads as disclosed in that patent. It will be understood that the heat exchanger units of the present invention may be constructed of tubes of any desired length to suit a particular installation. Also, as disclosed in that patent, the heat exchange units can be made in sections where it is desirable to employ a unit of extreme length.

The modified form of heat exchanger unit shown in Fig. 4 is like that of Fig. 1 except that bands 13 or 14 are employed to strengthen the unit; that is, to assist the brazing or welding of tubes and core strips in holding the unit together. The type of band indicated at 13 consists of a few turns of binding wire, while the type shown at 14 consists of a metal strip having its ends joined by brazing, welding, or the like. A given unit may be provided with either type applied in suitable spaced relation throughout its length.

In regard to the method of manufacturing the heat exchanger unit, when the core strips and tubes are to be secured together by brazing or hard soldering, the inner surfaces of the core strips C₁ are provided with a coating of appropriate welding metal having a fusing temperature which is lower than that of the tube or core material. Such coating is indicated at 15 in Fig. 5, and the inner core strips C₂ are coated all over with a layer 16 of similar welding metal. The various parts, including the four tubes, the four core strips C₁ and the two core strips C₂ are assembled in parallel relation as shown in Fig. 5, and temporary binding wires such as indicated

at 17 are applied at suitable intervals throughout the length of the bundle to hold the parts together. It will be understood that with the parts thus assembled, the surfaces of the tubes T₁, T₂, T₃ and T₄ will not necessarily be precisely tangent to one another or in contact with one another as shown in Fig. 5, but at least some of the tubes will be apt to be held in slightly spaced relation from their neighbors by the thicknesses of the core strips C₁ and C₂.

With the parts assembled as shown in Fig. 5 they are subjected to a brazing temperature in any suitable manner as, for example, by placing the entire bundle in an oven, or by passing the bundle through a continuous brazing apparatus adapted to apply brazing temperature to a portion only of the bundle at a given time. In Fig. 6 the relative positions of the tubes and core strips are shown after the brazing operation has been completed and the parts united thereby into a unitary structure, and the temporary binding wires 17 removed.

During the brazing operation appropriate pressure is applied to bring the four tubes into tangential contact with one another throughout their length as shown in Fig. 6. Such pressure may be applied either by means of the binding wires 17 or by other external and appropriate means. The apexes 1 and 2 of the respective core strips C₁ and C₂ disappear during the brazing operation and the brazing metal flows into and fills the vacant spaces or interstices shown in Fig. 5 adjacent these apexes. This causes the coatings 15 and 16 of the brazing metal to become somewhat thinner as shown in Fig. 6. The contacting surfaces of the respective tubes and core strips are united in intimate rigid contact throughout the extents of their surfaces and throughout the length of the heat exchanger unit.

When the parts of the heat exchanger unit are to be united by means of welding instead of brazing, the parts are assembled in a bundle similar to that shown in Fig. 5, but the coatings 15 and 16 of welding metal are omitted from the core strips. Then the assembled bundle is subjected to a welding operation, preferably in a continuous welding machine, causing the parts to be welded together as shown in Fig. 7. From this figure it will be understood that the interengaging surfaces of the core strips CW₁ and CW₂ are united by the welding of the surface metal of these strips and that of the respective tubes as indicated at 18 and 19. The metal of the core strips, while in the liquid condition fills the interstices between the tubes and cores, thus providing all metal heat flow paths between adjacent tubes.

Referring now to Figs. 8 and 9, there is here illustrated a further modified form of the invention. In this embodiment each of the tubes T₅, T₆, T₇ and T₈, one of which is shown in side view in Fig. 9, has circular end portions 20, and between these end portions are heat conducting cores CI, a portion of each core being integral with the metal of the tube. These core portions CI have flat interengaging surfaces 21 extending lengthwise of the tubes and the thickness of these integral core portions CI varies as may be seen in the cross-sectional view in Fig. 8 in such manner that the four tubes can be nested together with their respective flat surfaces 21 in engagement with one another. These several surfaces are united by films of welding metal 22 to combine the tubes into a unitary structure.

Tubes T₅ and T₇ are in cross section substantially the shape of a modified pentagon with one rounded corner, and tubes T₆ and T₈ are in cross section substantially trapezoidal with one rounded corner. With their flat sides in engagement with one another as described, and as shown in Fig. 8, the general outline of the unit in cross section is that of a parallelogram with rounded corners similar to the other forms of heat exchanger unit previously described.

The metal added along the central portions of the tubes and extending outwardly beyond the circular outlines (Fig. 7) of the end portions 20 of the tubes serves as core material forming paths between the several tubes for the transfer of heat in a manner similar to the heat transfer in the other embodiments of the invention.

It will be understood that the end portions 20 may be secured in a connecting flange similar to flange 6 in Fig. 1 and that at the opposite end of the unit, the proper tubes may be connected together by return bends similar to return bends 4 and 5.

By means of the present invention there has been provided a compact heat exchanger unit which is comparatively light in weight and is well adapted for use at both high pressures and high temperatures and which provides for the efficient transfer of the heat from the comparatively hotter fluid to the cooler fluid.

Although in the described embodiments two tubes are provided for hot fluids and two for cooler fluids, the number of tubes employed for each fluid may be varied as desired, and the invention is not limited to the number of cool and hot tubes shown. Thus the units may be of the single pass type with one or more tubes for each fluid and no return flow. When a plurality of passes is to be employed, two or more tubes are used for the hot fluid and two or more tubes for the cooler fluid. Different numbers of tubes may be used for the different fluids. For example, the unit may comprise three tubes for carrying one fluid and six tubes for carrying the other.

Also, the tube, or tubes, for carrying the hot fluid may be of different size from the tube, or tubes, for carrying the cooler fluid. In this way the fluids may be caused to flow at different velocities to establish the maximum rate of heat transfer between the two fluids for any particular installation. When either pair of tubes, for example tubes T₁ and T₃ is made smaller in diameter than the other pair T₂ and T₄, the cross section of the elongated outer and inner core strips may be modified correspondingly but the length of the path of heat conduction from tube to tube through the cores is not increased. Consequently, there is no change in the rate of heat transfer due to an increase in the length of the path of heat conduction from one tube to another. Should it be found desirable to do so, the diameter of one of the four tubes or of one of each pair of the tubes may be reduced or increased as required to produce the desired fluid velocity in that particular tube.

It should be understood that the embodiments of the invention selected for illustration are but typical of various forms in which the invention may be carried out and that the invention is not limited to the details of construction disclosed except in so far as set forth in the appended claims.

In the present application the filler strips and tubes are restrained against relative longitudinal movement under the forces of expansion and con-

traction, whereas in applicant's Patent No. 2,443-295, issued June 15, 1948, the parts are not so restrained.

I claim:

1. A built-up heat exchanger element including four substantially parallel originally discrete prefabricated thin-wall seamless metallic tubes, two of said tubes being in contact with each other and also in contact separately with each of the other two tubes, said four tubes thus forming two inner interstitial spaces of substantially triangular cross-section and four outer interstitial pockets of substantially triangular cross-section, and triangular prefabricated metal filler strips of substantially triangular cross-section disposed to occupy substantially all the free space in said spaces and pockets, said tubes and said strips being united structurally and thermally by a continuous metallic bond applied during fabrication of the element to unite all contiguous prefabricated metal surfaces.

2. A built-up heat exchanger element including four substantially parallel originally discrete prefabricated metallic tubes, two of said tubes being in mutual contact and also in contact separately with each of the other tubes, and a plurality of prefabricated metal fillers positioned to fill substantially all of the space between the outer walls of said tubes along substantially the entire lengths thereof, said tubes and fillers being united structurally and thermally by a continuous metal bond applied during fabrication of the element

to unite all contiguous metal surfaces and prevent relative longitudinal movement thereof.

3. A built-up heat exchanger element as defined in claim 2 in which each of said prefabricated metal fillers is integral with a prefabricated metallic tube.

WILLIAM BISCH.
